UNITED STATES PATENT OFFICE

MAURICE FRANÇOIS MOREAU, OF EPINOUE, FRANCE

MECHANICALLY DRIVEN MOWING MACHINE

Application filed April 2, 1927, Serial No. 180,529, and in France April 2, 1926.

In the mechanically driven mowing machines, which are now frequently used and adapted either for animal traction or for coupling at the rear of a truck, the reciprocating motion of the knife is due to the turning of the vehicle wheels and depends consequently on the movement of the mowing-machine.

In other kinds of machines, the knife is driven by an independent motor mounted on the frame.

The invention has for its object to provide a device which may be directly fastened on the truck and driven by the auxiliary or "driving pulley" which is supported on one side of the truck and connected directly to the motor shaft, said device allowing to fit directly on the other side a mowing machine comprising only the usual cutting and supporting parts, the aforesaid device being substituted to the driving parts.

This device, which is enclosed in a box fastened to the gear-case of the truck, comprises substantially a pulley with its shaft parallel to the shaft of the existing pulley directly driven by the engine, the first named pulley acting in combination with a level gear and transmitting directly the motion of the engine to the operating rod of the mowing-machine.

This device offers especially the following advantages:

(a) Use of the engine of the truck for driving the knife of the mowing-machine,

(b) Elasticity of the belt drive which prevents in a great measure the fractures of the knife frequently caused by the presence of a hard strange body,

(c) Possibility, due to the site of the crank disc, to use a very long rod, realizing a more flexible working,

(d) Variable speed of the knife independently from the advance of the truck,

(e) Adjustment of this device on the truck without modification of the existing elements.

This invention will be fully understood by means of the following description and annexed drawings, said description and drawings being chiefly given as indications.

Fig. 1 is an elevation of the device,

Fig. 2 is a sectional plan view,

Fig. 3 is an end view, the pulleys being removed,

Fig. 4 is a perspective view showing the invention applied on a Fordson truck,

Figs. 5 and 6 are respectively elevation and plan view showing how the driving parts of the mowing-machine are connected to the truck.

The ordinary pulley P of the truck which is directly connected to the motor shaft and not to the axle shaft of the truck wheels, transmits its rotary motion through a belt Q to another pulley A the shaft B of which is parallel to that of the aforesaid pulley P.

On said shaft B a level pinion C is keyed which drives at its turn a pinion D keyed on a shaft E which supports at its other end a crank disc G the pin of which receives the head of the rod I of the mowing-machine connected to the other side of the truck, on the left side in the drawings.

If the truck does not comprise a disengaging-gear for the pulley P, a loose pulley A¹ may be provided on the same shaft as pulley A.

The shafts B and E are centered and held in position by means of an abutment K and ball-bearings L fitted in a box M arranged as oil-bath.

The box M is fastened on the truck case S by means of a coupling plate N and a bracket O suitably shaped according to the truck case.

What I claim as my invention and desire to secure by Letters Patent is:—

A mowing machine attachment for a tractor, provided with a take-off pulley connected directly to the motor shaft, comprising in combination with cutting apparatus including a finger bar and a reciprocating cutter bar, means to attach the cutting apparatus to a tractor, a box having means whereby the same may be attached to the tractor, a pair of shafts arranged at right angles to each other and mounted in bearings with which said box is provided, said shafts being geared together and one of them being parallel with the axis of said take-off

pulley and provided with a pulley, an endless band connecting said pulleys, a crank disc carried by the other shaft and a rod pivoted on the crank of said disc and pivotally connected to the cutter bar of the mowing mechanism.

In testimony whereof I affix my signature.
MAURICE FRANCOIS MOREAU.
